BOAT ANCHOR HAVING PIVOTED ARMS

Forrest D. Wilson, Auburn, N. Y., assignor of forty percent to John H. Frost, Auburn, N. Y.

Application March 22, 1951, Serial No. 216,987

2 Claims. (Cl. 114—208)

This invention relates to boat anchors and has for its object an anchor which comprises a plurality of lever arms, usually a pair, formed with flukes at their front ends, the lever arms being pivoted between their ends, a shank to which the lever arms are pivoted and to which the anchor line is secured, and a float or buoyant member rigid with the lever arms in the rear of the pivot and usually also a weight rigid with the lever arms in the rear of the pivot, the combined weight of the rear portion of the lever arms, the float, and the weight, acting to slightly overbalance the flukes and the front portion of the lever arms and fold them about the pivot up alongside the shank when the anchor is lifted out of the water. When the anchor is dropped into the water, the float lifts the rear ends of the lever arms upwardly about the pivot, causing the flukes to incline downward to dig into the bottom of the body of water.

The invention consists in the novel features and in the combinations and constructions hereinafter set forth and claimed.

In describing this invention, reference is had to the accompanying drawings in which like characters designate corresponding parts in all the views.

Figure 1 is a view illustrating the anchor attached by the anchor line to the bow of a boat.

Figure 2 is a plan view of the anchor.

Figure 3 is a side elevation thereof, the position of the anchor when in the water being indicated in broken lines.

Figure 4 is a fragmentary view of the upper end of the shank of the anchor showing the shank embracing the pulley on the boat, over which the anchor rope runs when the anchor is pulled up.

The numeral 1 designates the body of the anchor consisting of a pair of fluke carrying arms 2 pivoted at 3 between their ends to the shank 4 to which the anchor line 5 from the boat B is secured. 6 are the flukes at the front ends of the lever arms 2. The shank 4 is also double or bifurcated, and the pivot 3 is a pin or shaft extending through two aligned bearing openings in the bifurcations of the body 1, and of the shank 4.

7 designates a float or buoyant body rigid with the lever arms on the opposite side of the pivot 3 to that on which the flukes 6 are located—that is, on the rear of the lever arms.

8 is a counterweight rigid with the lever arms 2 in the rear of the pivot 3. The combined weight of the float and the lever arms 2 in the rear of the pivot 3 and the counterweight 8 is sufficient to slightly overbalance the fluke carrying arms and fold them upward alongside the shank, when the anchor is lifted out of the water. When the anchor enters the water, the rear end of the body 1 and the weight 8 is buoyed up by the float 7 and the flukes shifted to point downward at an inclined angle, as shown in dotted lines, Figure 3, and hook into the bottom of the body of water. The pivotal movement downward of the fluke carrying arms 2 is limited by the weight coming in contact with the shank 4 at 9.

The bifurcations of the shank 4 are spaced apart and secured together by a pair of tie bolts 10 with spacers thereon to which the anchor rope or line is secured.

2

The tie bolts 10 are located a sufficient distance below the upper end of the shank 4 to provide upstanding ears or a recess 11 to embrace the pulley of the anchor rope guide on the boat when the anchor is fully pulled up. 5 The location of the tie bolts provide ample space for the knot of the rope tied to the tie rods between the ears 11 and also for the ears to embrace or straddle the side of the rope guide or pulley 12.

By the shank and rope arrangement, the anchor is firmly held to the boat by the anchor or tie rope when the anchor is fully out of the water, and also the anchor can be lowered into the water by means of the tie or anchor rope without the operator leaving his position or seat in the boat.

15 Owing to the pivotal arrangement of the fluke carrying arms and the shank 4 and to the location of the float and the counterweight relative to the pivot, the anchor is easily handled or placed into and removed from the water. When being removed, the flukes fold up into vertical position alongside the shank and when being dropped into the water, the float elevates the rear ends of the fluke carrying levers, causing the flukes to point downward at an oblique angle in position to dig into the bottom of the body of water.

25 What I claim is:

1. A boat anchor comprising a shank having a pivot pin at one end and being provided with means located intermediate its ends for the attachment of the anchor rope, a pair of arms mounted on said pivot pin intermediate their ends, like end portions of said arms diverging outwardly from said shank and flukes mounted on said ends of the arms, a float rigidly mounted on the opposite ends of the arms, said arms assuming a vertical position parallel with the shank with the diverging fluke ends of the arms extending upwardly when the anchor is out of the water, said float being operable when the anchor is submerged to tilt the arms about said pivot pin and move the fluke ends of the arms downwardly into an oblique angle with the shank, and stop means limiting pivotal movement of the arms under the buoyant action of the float.

2. A boat anchor comprising a shank having spaced apart side walls and tie bolts between the side walls and located intermediate the upper and lower ends of the shank and providing means for the attachment of the anchor rope, a pivot pin mounted in the lower ends of said side walls, the side walls providing a space for the knot of the anchor rope and extending upwardly from said tie bolts to form spaced ears at the upper end of the shank to embrace the sides of the guide on the boat for the anchor rope when the anchor is pulled up against the boat, a pair of arms mounted on said pivot pin intermediate their ends, flukes mounted on like ends of the arms and a float rigidly mounted on the opposite ends of the arms, said arms assuming a vertical position parallel to the shank with the fluke ends of the arms extending upwardly in juxtaposition to said ears when the anchor is out of the water, said float being operable when the anchor is submerged to tilt the arms about said pivot pin and move the fluke ends of the arms downward into an oblique angle with the shank, and stop means for limiting the pivotal movement of the arms under the buoyant action of the float.
